CLAIM

The ornamental design for a nail polish container, as shown and described.

DESCRIPTION

FIG. 1 is a perspective view of a nail polish container, showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an exploded perspective view.

The broken lines shown illustrate portions of the nail polish container and form no part of the claimed design.

1 Claim, 8 Drawing Sheets
